CLAIM

The ornamental design for a portable phone cradle, as shown and described.

DESCRIPTION

FIG. 1 is a front elevation view of the portable phone cradle showing my new design;

FIG. 2 is a left side elevation view thereof;

FIG. 3 is a right side elevation view thereof;

FIG. 4 is a back elevation view thereof;

FIG. 5 is a top plan view thereof; and,

FIG. 6 is a bottom view thereof.

The broken line showing of environmental structures is for illustrative purposes only and forms no part of the claimed design.
